UNITED STATES PATENT OFFICE.

CHARLES LEA, OF BOSTON, MASSACHUSETTS, ASSIGNOR TO THE AUTOMATIC MERCHANTIZER INC., OF BOSTON, MASSACHUSETTS, A CORPORATION OF DELAWARE.

COIN-CONTROLLED MECHANISM.

Application filed July 15, 1926. Serial No. 122,624.

My invention relates to coin controlled mechanism particularly but not exclusively adapted for use in vending machines.

The invention will be best understood from the following description when read in the light of the accompanying drawings of an example of the invention, the scope of the invention being more particularly pointed out in the appended claims.

In the drawings:—

Fig. 1 shows a front elevation with parts in section of a vending machine constructed according to the invention;

Fig. 2 is a transverse section through the coin controlled mechanism;

Fig. 3 is a view according to Fig. 2 with parts in another position;

Figs. 4, 5, 6 and 7 respectively are sections on the lines 4—4, 5—5, 6—6 and 7—7 of Fig. 2;

Fig. 8 is a section on the line 8—8 of Fig. 1 with the parts in a different position;

Fig. 9 is a section on the line 9—9 of Fig. 8;

Fig. 10 is a plan of the article supporting member; and

Fig. 11 is a fragment of the front of the cabinet with the coin controlled mechanism and retaining member removed.

The vending machine illustrated is claimed and more fully described in my copending application Serial No. 122,623, filed herewith, and herein will not be described except so far as necessary to show how it cooperates with the present invention.

Referring to the drawings I have shown a cabinet arranged to maintain a stack of articles A, each of which articles is supported upon an article-supporting-member 1, the lowermost member of the stack being supported at opposite ends upon flanges or shelves 3 and 5. As illustrated the article-supporting-members are provided at opposite sides with slots 7 slidably engaging the fixed vertical guide members 9, said guide members terminating as indicated at 11 in Fig. 9 above the flanges 5 so that the lowermost article-supporting-member of the stack is disengaged from the guide members, thus permitting said article-supporting-member to slide on the flange members 3 and 5.

The releasing mechanism herein comprises the rod 13 having a head 15 adapted to be received by perforations 17 in the article-supporting-members. The rod 13 is shown

as formed integrally with the laterally projecting plate 19 the thickness of which is less than the diameter of the rod, the plate being pivotally carried by the cabinet 21 and having formed integrally therewith an arm 60 23 connected at its lower end by a link 25 to a reciprocatory member 27 of the coin controlled mechanism.

When the member 27 is moved toward the back of the cabinet to bring the rod into its dotted line position shown by Fig. 1, the head 15 is moved into the position shown by Fig. 9, and the lowermost article-supporting-member 1 is moved to the left, as viewed in Fig. 1, far enough to move its right hand end off the supporting flange 5, which permits said article-supporting-member to fall. The falling article is caught by a chute 29 and discharged through an opening 31 in the front of the cabinet, while the article-supporting-member falls through an opening in the plate toward a plate 33 upon which the discharged article-supporting-members are stacked, the article-supporting-member being provided with the slot 34 to 70 permit it to pass the plate 19.

The coin controlled lock mechanism herein illustrated comprises a casing 35 having a front flange 37 and a back flange 39, the latter about its marginal portion 85 being separated from the former by a groove 41 (Figs. 6 and 7) the thickness of which groove corresponds to the thickness of the material forming the lower portion of the front wall 43 of the cabinet. As indicated in Fig. 11 the lower portion of the front wall of the cabinet extends from the base 45 of the cabinet to a band 47 encircling the cabinet, being secured preferably by welding to said base and to said band. At 95 its middle portion the front wall of the cabinet is cut away as indicated at 49 (Fig. 11), the edges of this cut away portion being notched as indicated at 51, while the marginal portion of the back flange 39 is notched at 53 (Fig. 6). By this construction the casing 35 may be presented to the front wall 43 of the cabinet with the cut away portions 53 of the flange 39 in registry with the projecting portions 55 of the cut away part of said wall, and with the notches 51 of this cut away portion respectively in registry with those parts of the flange 39 which lie above and below the notches 53 in said flange. This enables the casing to be slid 105 110

downward to cause the projecting portions 55 of the wall to enter the portions of the groove 41 above the notches 53, and the portions of the wall at the edges of the cut 5 away part below the lower notches 51 to enter the portions of the groove 41 below the notches 53. The casing is held in position by means of a plate 57 the width of which corresponds to the width of the cut 10 away portion 49 of the plate 53, the lower end of the plate entering the upper horizontal portion of the groove 41 and being secured to the band 47 by means of a stud 59 carried by said band and a nut 61 screwed 16 on the stud.

The upper portion of the flange 37 of the casing 35 of the coin controlled mechanism is cut away as indicated at 63 (Fig. 6), the flange being formed with a vertical slot 65 20 communicating with this cut away portion and extending throughout the length of the flange to provide in cooperation with the plate 57 and front wall 43 a slot for receiving the coin indicated at B.

As illustrated the casing 35 has reciprocably mounted therein the plunger member 27 the body of which member is of rectangular cross-section and has a cylindrical portion 68 projecting from the front of said casing. At its rearward end the member 27 has spaced extensions 69 in which is mounted a trunnion 71 to which is secured the link 25. It will therefore be observed that by pressing the part 69 of the reciprocable plunger member inward the releasing mechanism hereinbefore described may be actuated to discharge an article. Upon release of the hand of the operator from the part 69 the reciprocable member is returned to its position indicated by Figs. 1 and 2 by means of the spring 73 connected at opposite ends respectively to the plate 57 and arm 23.

The lower side of the reciprocable member 27 is shown as formed with a slot 75 45 in which is mounted a plate 77 having a lost motion connection with said member afforded by a slot 79 formed in the plate and a lug 81 carried by said member and projecting into said slot. Pivoted to the casing 35 is a pawl 83 which normally bears against the bottom of the reciprocable member in the path of the rearward end of the plate 77, which construction in the absence 50 of the coin will prevent sufficient movement of said member to operate the article releasing mechanism.

The reciprocable mechanism 27 as herein illustrated is formed with a pair of slots 85 and 87. When the coin is inserted through the slot 65 it is received by the slot 85 and rests upon the upper side of the plate 77. When the reciprocable member is moved forward from its position shown by Fig. 1 the plate 77 contacts with the end of the pawl 83 and remains stationary. The lost mo-

tion between the plate and the reciprocable member however is sufficient to permit the reciprocable member to move inward far enough to transfer the coin from the plate to the upper side of the pawl, as indicated by the coin in its dotted line position in Fig. 2. Cooperating with the top of the edge of the coin when in this dotted line position is a member 89 fixedly carried by the casing and having the front end of its lower surface formed as a cam surface 91 effective upon continued movement of the reciprocable member to press the coin downward to move the pawl out of engagement with the plate 77 as indicated in Fig. 3. The pawl now being released from the plate 77 the reciprocable member may be moved inward far enough to effect release of an article-supporting-member and to move the coin past the pawl, which permits the coin to drop from the slot 85 into the cup 92 at the bottom of the cabinet.

As illustrated, the plate 77 is held in predetermined relation to the member 27 by means of a spring pressed plunger 93 carried by said member and adapted to engage either of two recesses 95 formed in the upper side of the plate 77. Consequently if the reciprocable member is in the position shown by Fig. 3, and the coin is of insufficient diameter to cause the pawl 83 to be released from the plate 77, the plate, on the return stroke of said member, due to the fact that in this position the spring pressed plunger engages with the rearward recess 95, will move away from the end of the pawl before the coin reaches the end of the pawl, and this will permit the coin to be discharged through the lower end of the slot 65 into the cup 97 at the front of the cabinet. When the forward end of the plate hits the front wall 99 of the casing 35 on the return stroke of the reciprocable member the plate will come to rest to cause the plunger and plate to assume the relative position shown in Fig. 2 so that when a new coin is inserted it will rest on the top of the plate. In the position shown by Fig. 2 the plunger 93 is in engagement with the forward recess 95 of the plate 77 which causes the plate to move with the plunger until the plate strikes the pawl.

A magnet 101 is shown secured to the upper side of the casing, the poles 103 of which magnet are placed opposite the top of the slot 65 so that if a spurious coin of magnetic material is placed in the slot 65 it will be deflected toward the slot 87 in the reciprocable member, the lower end of which slot normally is not covered by the plate 77, and such coin therefore will fall through said slot into the lower half of the slot 65 and be discharged into the cup 97.

For guiding the coins into the lower end of the slot 65 the bottom of the cut away

portion 49 of the plate 43 has an upwardly projecting tongue 105 which is bent inward, as shown in Fig. 2, to catch the spurious coins passing through the slot 87 and the undersized coins which drop from the slot 85 when the reciprocable member is returned to move the slot 85 away from the pawl.

Herein the upper sides of the projecting portions 69 of the reciprocable member are formed with rack teeth 107 which cooperate with a swinging pawl 109 carried by the casing 35. When the pawl 83 is released the pawl 109 moves into engagement with the rack teeth, which prevents return of the member 27 until said member is moved inward far enough to cause disengagement of an article. At the inner end of the rack teeth the projections 69 are formed with deep notches 111 permitting the pawl 109 to disengage the rack teeth and move in the vertical position so that the pawl 109 during the return stroke of the member 27 will engage the rack teeth while inclined in the opposite direction to that shown in Fig. 3, thereby preventing operation of said member for discharging a second article without moving said member back to its initial position and inserting a new coin.

Suitable means may be provided for rendering the mechanism inoperative to receive coins after the last article of the stack of articles is discharged. For this purpose a member 113 is herein provided, which member rests upon the uppermost member of the stack of article-supporting-members 1, and is provided with slots 115 engaging the guide members 9 so that the perforation 117 formed in said member 113 will receive the head 15 of the rod 13 when the latter is moved to discharge the uppermost article-supporting-member 1. The member 113 is of sufficient thickness to cause it, when it rests upon the shelf 5, to engage the guide members 9 and therefore prevent movement of the rod 13 from its position shown by Fig. 9 to that shown by Fig. 1. It will be observed from Figs. 2 and 3 that when the coin receiving member 27 is in the position corresponding to the position of the rod 13 in Fig. 9 the coin slot 85 is out of registry with the coin slot 65, and therefore when the member 113 engages the rod 13 a coin cannot be wholly inserted in the machine.

It will be understood that I am not limited to the example of the invention herein described and that within the scope of the invention wide deviations may be made therefrom without departing from the spirit of the invention.

60 Claims:

1. A coin controlled apparatus having, in combination, a reciprocatory member, a locking member, a part for engagement with said locking member connected to said reciprocatory member for relative movement

to permit limited movement of said reciprocatory member, and means rendered operative by a coin when inserted for disengaging said part and locking member upon such limited movement of said reciprocatory member to 70 permit extended movement of said reciprocatory member.

2. A coin controlled apparatus having, in combination, a reciprocatory member, a locking member, a part for engagement with said locking member connected to said reciprocatory member for relative movement to permit limited movement of said reciprocatory member, and means rendered operative by a coin when inserted for disengaging said part and locking member upon such limited movement of said reciprocatory member to permit extended movement of said reciprocatory member, said last mentioned means comprising a cam cooperating 85 with the coin.

3. A coin controlled apparatus having, in combination, a reciprocatory member, a locking member, a part for engagement with said locking member connected to said reciprocatory member for relative movement to permit limited movement of said reciprocatory member, means providing a cam surface, and said reciprocatory member and said part acting to receive a coin and move it 95 against said cam surface to cause said coin to effect disengagement of said part and locking member upon said limited movement of said reciprocatory member.

4. A coin controlled apparatus having, in combination, a reciprocatory member, a locking member, a part for engagement with said locking member connected to said reciprocatory member for relative movement to permit limited movement of said reciprocatory member, means providing a cam surface, said reciprocatory member and said part acting to receive a coin and move it against said cam surface to move said coin relative to said reciprocatory member, and means actuated by such relative movement of said coin for effecting disengagement of said part and locking member.

5. A coin controlled apparatus having, in combination, a reciprocatory member, a locking member, a part for engagement with said locking member connected to said reciprocatory member for relative movement to permit limited movement of said reciprocatory member, means providing a cam surface, said reciprocatory member and said part acting to receive a coin and move it between said cam surface and said locking member upon such limited movement of said reciprocatory member for moving said locking member out of engagement with said part.

6. A coin controlled apparatus having in combination, a reciprocatory member, a part movable with said member and having 136

- a lost motion connection to it, a locking member for engaging said part, said reciprocatory member formed for receiving a coin and by said lost motion connection transferring said coin to said locking member, and means to cause said coin to move said locking member out of engagement with said part while said lost motion is being taken up.
7. A coin controlled apparatus having in combination, a reciprocatory member, a reciprocatory part movable with said member and having a lost motion connection to it, a locking member for engaging said part, said reciprocatory member formed for receiving a coin and by said lost motion connection transferring said coin to said locking member, and means to cause said coin to move said locking member out of engagement with said part while said lost motion is being taken up.
8. A coin controlled apparatus having, in combination, a reciprocatory member, a reciprocatory part movable with said member and having a lost motion connection to it, a swinging locking member for engaging said part, said reciprocatory member formed for receiving a coin and by said lost motion connection transferring said coin to said locking member, and means to cause said coin to move said locking member out of engagement with said part while said lost motion is being taken up.
9. A coin controlled apparatus having, in combination, a reciprocatory member, a reciprocatory part moving with said member and having a lost motion connection therewith, a locking member normally in the path of said part, means responsive to the pressure of a coin for causing said locking member to be moved from the path of said part while said lost motion is being taken up when said reciprocatory member is moved in one direction, and means for causing return motion to discharge a coin through the space between said part and locking member before said lost motion is taken up on the return stroke if said locking member is not moved from the path of said part.
10. A coin controlled apparatus having, in combination, a reciprocatory member, a cooperating reciprocatory part having a lost motion connection thereto, a locking member in the path of said part, said reciprocatory member formed for receiving a coin supported upon said part whereby movement of said member transfers said coin to said locking member, and means for cooperation with the coin when transferred for moving said locking member from the path of said part.
11. A coin controlled apparatus having, in combination, a reciprocatory member, a cooperating reciprocatory part having a lost motion connection thereto, a locking mem-
- ber in the path of said part, said reciprocatory member having a slot for receiving a coin, said slot closed by said part whereby movement of said member transfers said coin to said locking member, and means for cooperation with the coin when transferred for moving said locking member from the path of said part.
12. A coin controlled apparatus having, in combination, a reciprocatory member formed with a slot for receiving a coin, a reciprocatory part closing the bottom of said slot, means providing a lost motion connection between said member and part, a locking member cooperating with said part, motion of said reciprocatory member sufficient to take up the lost motion between it and said part transferring the coin to said locking member, and means cooperating with the coin for moving said locking member from engagement with said part.
13. A coin controlled apparatus having, in combination, a reciprocatory member formed with a slot for receiving a coin, a reciprocatory part closing the bottom of said slot, means providing a lost motion connection between said member and part, a locking member cooperating with said part, said locking member normally spaced from said part a distance greater than the width of a coin, motion of said reciprocatory member sufficient to take up the lost motion between it and said part transferring the coin to said locking member, and means cooperating with the coin for moving said locking member for engagement with said part.
14. A coin controlled apparatus having, in combination, a reciprocatory member formed with a slot for receiving a coin, a reciprocatory part closing the bottom of said slot, means providing a lost motion connection between said member and part, a locking member cooperating with said part, said locking member normally spaced from said part a distance greater than the width of a coin, a second slot formed in said reciprocatory member opening to the space between said part and locking member, guiding means for directing a coin to fall toward the first mentioned slot, a magnet for directing falling coins of magnetic material toward said second mentioned slot, motion of said reciprocatory member sufficient to take up the lost motion between it and said part transferring the coin received by said first mentioned slot to said locking member, and means cooperating with the coin for moving said locking member from engagement with said part.
15. A coin controlled apparatus having, in combination, a movable member, locking means therefor comprising a pawl and a part moved by said movable member, said part and movable member being operatively connected by means permitting limited

movement of said member when said part is engaged by said pawl, means responsive to the pressure of a coin for disengaging said pawl from said part upon such limited movement of said member, said part and member cooperating for retaining and moving said coin for actuation of said means, and means for positioning said part in predetermined relation to said reciprocatory member for retaining said coin when said pawl is positioned for engagement with said part and for preventing retaining of said coin when said pawl is moved for engagement with said part.

16. A coin controlled apparatus having, in combination, a movable member, locking means therefor comprising a pawl and a part moved by said movable member, said part and movable member being operatively connected by means permitting limited movement of said member when said part is engaged by said pawl, means responsive to the pressure of a coin for disengaging said pawl from said part upon such limited movement of said member, said part and member cooperating for retaining and moving said coin for actuation of said means, and means for resiliently positioning said part in predetermined relation to said reciprocatory member for retaining said coin when said pawl is positioned for engagement with said part and for preventing retaining of said coin when said pawl is moved for engagement with said part.

17. A coin controlled apparatus having, in combination, a movable member, locking means therefor comprising a pawl and a part moved by said movable member, said part and movable member being operatively connected by means permitting limited movement of said member when said part is engaged by said pawl, said member having a coin receiving slot closed at one end by said part when said part is in one position relative to said member, engagement of said part with said pawl moving said part relative to said member for opening said end of said slot, means for resiliently holding said part to said member in the positions of said part in which it closes and opens said slot, and means whereby said limited movement of said member causes the coin to move said pawl from engagement with said part.

18. A coin controlled apparatus having, in combination, a member movable from an initial position to a final position and back to said initial position, a part having a lost motion connection to said member, spaced stops one of which is a movable pawl for

moving said part relative to said member when the latter is reciprocated, means resiliently holding said part to said member in the positions to which it is moved relative to said member by said spaced stops, said part cooperating with said member to retain a coin when said part and member are in one of their relative positions, and means cooperating with the coin for moving said pawl from engagement with said part when said member is moved to take up said lost motion.

19. A vending machine having, in combination, means for maintaining a stack of articles, coin controlled mechanism comprising an actuator and a part operated thereby for releasing the articles one by one, said mechanism having provision for a coin to release said actuator for movement, a member supported on the stack of articles for engaging said part for preventing operation of said mechanism when the articles of said stack are discharged.

20. A vending machine having, in combination, a plurality of releasable members each for supporting an article of a stack of articles, a finger for actuating release of the members at the bottom of said stack for successively discharging articles, a member at the top of said stack for engaging said finger, said last named member being restrained against release, coin controlled mechanism comprising an actuator positively connected to said finger by means preventing substantial movement of said actuator when said finger is engaged by said member at the top of said stack.

21. A vending machine, having in combination, means for maintaining a stack of articles comprising a plurality of superimposed releasable members, means for actuating successive release of said members comprising a part for engaging and moving said members, an actuator for said part positively connected thereto, said actuator having a coin receiving pocket, means providing a coin receiving slot normally aligned with said pocket, a member at the top of said stack retained against release whereby to lock said part and said actuator against substantial movement upon discharge of the articles of said stack, said slot and pocket being out of alignment when said members are released and said member at the top of said stack engages said part.

In testimony whereof, I have signed my name to this specification.

CHARLES LEA.
